CLAIM

We claim the ornamental design for a trans-hybrid golf club head, as shown and described.

DESCRIPTION

FIG. 1 is an isometric view of a trans-hybrid golf club head showing our new design;

FIG. 2 is a rear elevation view thereof;

FIG. 3 is a front elevation view thereof;

FIG. 4 is a bottom plan view thereof;

FIG. 5 is a top plan view thereof;

FIG. 6 is a toe side elevation view thereof; and,

FIG. 7 is a heel side elevation view thereof.

The broken lines are for illustrative purposes only and form no part of the claimed invention.
